W. WYAND

FURNACE GRATE

Filed Aug. 28, 1924

FIG. 1.

FIG. 2.

FIG. 3.

FIG. 4.

Inventor
William Wyand
by Robert W. Jenner
Attorney

UNITED STATES PATENT OFFICE.

WILLIAM WYAND, OF ABSECON, NEW JERSEY.

FURNACE GRATE.

Application filed August 28, 1924. Serial No. 734,669.

To all whom it may concern:

Be it known that I, WILLIAM WYAND, a citizen of the United States, residing at Absecon, in the county of Atlantic and 5 State of New Jersey, have invented certain new and useful Improvements in Furnace Grates, of which the following is a specification.

This invention relates to boiler furnaces 10 specially adapted for burning low grade coal or culm; and it consists of a frame for supporting the grate bars or fuel plates, provided with passages for cooling fluid as hereinafter fully described and claimed.

15 In the drawings, Figure 1 is a cross-section through a grate and an ash-pit, showing the frame provided with passages for air. Fig. 2 is a plan view of the end portions of the frame and portions of the 20 fuel plates. Fig. 3 is a side view of a portion of one of the deflecting plates drawn to a larger scale. Fig. 4 is a plan view of the same. Fig. 5 is a cross-section through one of the hollow bars of the frame showing it modified so that water can be used 25 instead of air for the purpose of cooling it.

The frame is provided with a series of 30 hollow longitudinal bars 8 arranged parallel to each other. These bars are connected at one end to a hollow front end bar 9 to 35 which a pipe 10 is attached for the supply of cooling fluid under pressure. Air is preferably used, but in some cases water may be used, and the construction is then modified accordingly.

The rear ends of the bars 8 are closed, and they are preferably secured to an end bar 10, which need not be a hollow bar when air is used as the cooling fluid. The 40 bars 8, 9 and 10 may be formed integral with each other, or they may be formed separately and secured together in any approved way. Distance pieces 12 are arranged between the longitudinal bars 8 at suitable points, but may be omitted if the 45 frame is a short one. Any number of frames may be secured side by side.

The longitudinal bars 8 are preferably 50 oval in cross-section, and they have longitudinal ribs 14 at their tops, and shoulders 15 for supporting the grate bars or fuel plates 16. The shoulders may be on the bars, or they may be beveled sides of the ribs 14. Upwardly converging air passages 13 are 55 formed between the lower parts of the bars 8. The grate bars or fuel plates 16 are of

any approved form provided with a multiplicity of small air passages 17, and their edges are adapted to rest against the ribs or on the shoulders 15. The bottoms of the 60 longitudinal bars 8 are provided with outlet openings when air is used as the cooling fluid, and these openings may be narrow slots 18 of any suitable length or holes 18' of any suitable size and shape. The bars 8 65 are integrally-formed, and the lower parts of the convex sides of the adjacent bars form the upwardly converging passages or air spaces 13. The air discharged from the outlets 18 is brought in contact with the 70 outsides of the bars in these spaces 13, and is again heated on its way upward to pass through the small openings of the fuel plates which are supported over the air 75 spaces 13.

The tops of the ribs 14 and of the distance pieces 12 are shown flush with the tops of the fuel plates. It is not desirable for the distance pieces to project above the fuel plates as that would interfere with running 80 a poker lengthwise under the fuel in stoking, but the ribs 14 can be of any desired height.

Each longitudinal bar 8 is provided with one or more deflecting devices or plates 20. 85 Each deflecting plate has a shank 21 which is preferably cast in the metal at the upper part of the bar under the rib 14. The deflecting plate may however be secured in any other approved way so that it depends 90 within the hollow bar. Each deflecting plate is provided with a series of tongues 22 bent right and left alternately, and if desired twisted, as shown.

These tongues project in the hollow bars 95 and oblige the cooling fluid to follow a tortuous course. They also deflect all parts of the cooling fluid repeatedly against the sides of the bars, and they increase the area of surface exposed to the cooling fluid.

When air is used as the cooling fluid the frame is supported in a combustion chamber 24 over a closed ash-pit 25. Air is forced under pressure into the front ends of the longitudinal bars 8 so that it cools them, and passes out of them downwardly through their outlet openings 18, and thence upwardly through the air passages 17 of the grate bars, as indicated by the curved arrows in Fig. 1, after being suitably heated 105 by contact with the longitudinal bars and their deflecting plates.

When water is used as the cooling fluid the longitudinal bars 8' have imperforate bottoms as shown in Fig. 5, but have the deflecting plates 20 as hereinbefore described, and the water is let out at the rear ends of the bars 8'. These bars 8' can also be used for air, if desired.

The air to support combustion is forced from the ash-pit upwardly through the passages in the grate bars, but is warmed to a less extent than when forced through the longitudinal bars 8.

The air is forced through the fuel in small streams, and the pre-heating of it facilitates the combustion, and also prevents the frame from burning out quickly.

What I claim is:

1. In a furnace grate, a frame provided with tubular bars having convex sides, said bars being spaced apart to form air spaces and provided at their tops with ribs for supporting fuel plates over the said air spaces, and deflecting plates secured within the said bars and operating to deflect cooling fluid against their walls.

2. In a furnace grate, a frame provided with tubular bars having convex sides, said

bars having also air outlets in their bottoms, upwardly converging air spaces being formed between the convex lower portions of adjacent bars, which spaces receive the air from the said outlets, and said bars having also means for supporting fuel plates over the said air spaces.

3. The combination, with a frame provided with tubular bars as set forth in claim 2, of a closed ash-pit below the frame so that the air forced through the said bars is constrained to pass upwardly through the said converging spaces between them.

4. In a furnace grate, a frame provided with tubular bars arranged parallel to each other and having convex adjacent side portions which form an air passage which widens out upwardly and downwardly from the middle of the convex side portions, said bars having also air outlets at their bottoms and means for supporting a fuel plate at their upper parts over the said air passage to which air is supplied from the said outlets.

In testimony whereof I have affixed my signature.

WILLIAM WYAND.
